UNITED STATES PATENT OFFICE.

CHESTER M. LEFEW, OF HUDDY, KENTUCKY.

RAILWAY-FROG POINT.

Application filed September 12, 1927. Serial No. 219,040.

My invention relates to improvements in railway frog points, and the same relates more particularly to a detachable frog point for railways wherein the said point may be 5 reversed in compensating for the wear thereof.

Especially in coal mine tracks serious problems arise concerning the quick wiring of the frog points. The main purpose of 10 this invention is to overcome these problems, and to provide such a switch point which will require considerable less attention than the old type of frog.

An object of my invention is to provide 15 a detachable frog point for railway trackage, which is simple and very efficient for the purpose.

Another object resides in providing such 20 a detachable frog point which may be easily reversed in the event should one of the points thereof become worn.

Whereas my improved frog point is primarily intended for use on mine trackage, the same is equally suitable for use on regular 25 steam railways.

Other objects and advantages will become apparent as my invention is better understood from the specification and claim to follow.

30 In the drawing:—

Figure 1 is a top plan view of a railway frog, showing the frog point with my detachable and reversible point associated therewith, and

35 Fig. 2 is a perspective elevation of the diamond-shaped frog point insert.

For a more detailed description of my invention, I now refer to the drawings, in

which like numerals designate like parts. As is clearly shown in Fig. 1 of the drawing, the numeral 1 designates the associated pieces of trackage adjacent the switch point rails 2.

At the point of the aforesaid rails 2, I 40 form the same with a V-shaped socket 3. 45 The diamond-shaped insert member 4 is formed with points 5 and 6. Adjacent the pointed end of the insert 4 are formed a pair of openings 7 extending therethrough.

In application, one pointed end of the 50 insert is adapted to be disposed in the socket formed at the end of the frog rails 2. In this position, the insert is secured in place by suitable screws, or bolts, extending through the holes 7 in attaching relation 55 with the lower portion of the rails 2.

The opposite pointed end of the insert is 60 adapted to aline with the side of the frog rails 2. Ultimately when the insert point is exposed or becomes worn, the screws may be 65 removed and the insert reversed in respect to the socketed end of the frog rails 2. The insert 4 may be constructed of any material which will be durable, and will afford the greatest resistance against wear. 65

Having thus described my invention, what I claim as new is:—

In a wear compensating insert for railway track frog points, wherein the said point is formed with a V-shaped socket therein, a 70 diamond-shaped insert adapted for reversible association with respect to the socketed end of the frog point.

In testimony whereof I affix my signature.

CHESTER M. LEFEW.
